SCOURING PAD HOLDER

John W. Vaessen, West De Pere, Wis.

Application March 28, 1945, Serial No. 585,353

3 Claims. (Cl. 15—209)

1

This invention relates to a holder for scouring pads, and one of its objects is to provide a simple and inexpensive holder by which a scouring pad may be secured in place for service and when worn down may be replaced with a new scouring pad.

Another object of the invention is the provision of a scouring pad holder with a series of holding hooks, which may be forced into the scouring pad by screw pressure, and which will detachably hold the scouring pad in place on the holder.

A further object of the invention is to provide a holder for scouring pads with a screw mounted centrally in the holder and arranged to force a head inwardly and outwardly on the holder, whereby gripping prongs or hooks carried by the head may be forced into a new scouring pad to clamp the same against the holder, or forced away from the holder to release a used scouring pad.

With the above and other objects in view the invention consists in certain new and useful constructions, combinations, and arrangements of parts, clearly described in the following specification, and fully illustrated in the accompanying drawings, in which—

Fig. 1 is a perspective view of one form of the improved scouring pad holder.

Fig. 2 is a side elevation thereof.

Fig. 3 is a bottom plan view thereof.

Fig. 4 is a vertical sectional view, taken on line 4—4 of Fig. 2, looking in the direction of the arrows.

Fig. 5 is a side elevation of another form of the invention, partly in section.

Fig. 6 is a bottom plan view thereof.

Fig. 7 is a vertical sectional view, taken on line 7—7 of Fig. 5, looking in the direction of the arrows.

Fig. 8 is a horizontal sectional view, taken on line 8—8 of Fig. 7, looking in the direction of the arrows.

Fig. 9 is a top plan view of another form of the invention.

Fig. 10 is a bottom plan view thereof.

Fig. 11 is a vertical sectional view, taken on line 11—11 of Fig. 9, looking in the direction of the arrows.

Referring to the accompanying drawings, and particularly to Figs. 1 to 4, inclusive 5 designates a disc having a central handle 6 formed integral therewith, or formed of a separate piece of stock or material. The disc is provided with a central circular hole or opening 7, and the handle is pro-

vided with a central recess 8, of the same diameter as the hole or opening 7.

A screw 9 is extended through a small hole 10 formed in the end of the handle 6, and a cross head 11 is secured to the inner end of this screw. On this cross head a series of hooks or gripping prongs 12 is arranged, each hook or prong being formed U-shaped to provide an upwardly extending outer pad piercing arm 13, which is shorter than the inner arm 14, and which extends outwardly to a point approximately midway of the outer side of the disc 5 and the margin of the hole 7 thereof, and the disc is formed with radial slots 15 which receive the pointed ends of the arms 13. The cross head 11 is circular in form, so that it will not bite into the wall of the hole 7.

The upper end of the screw 9 is equipped with a thumb or wing nut 16, and when this thumb or wing nut is threaded tightly on the screw 9 against the upper end of the central handle or knob the head 11 will be drawn into the hole 7, and a scouring pad placed initially on the arms 13 will be clamped against the bottom face of the disc, and portions of the scouring pad will be forced into the radial slots or grooves 15. The interlocking engagement of the arms 13 with the radial slots will prevent the screw from turning in the handle and disc.

In Figs. 5 to 8, inclusive, I show a modified form of the invention, wherein the disc 20 and the handle 21 are constructed like the disc 5 and the handle 6, but the screw 22 has its head 22d seated in a countersunk recess 22b formed in the handle 21, and engage by a swivel connection 23 the cross head 24, which is circular in form. The screw also has threaded engagement with the second cross head 25, which is also of circular form.

The cross head 25 carries the gripping prongs 26, each of which includes a long shank 26a, and an L-shaped outer arm 26b, the terminal 26c of which is bent upwardly against the disc 20. These prongs or hooks have sliding engagement with the cross head 24, as the long shanks 26a of these prongs or hooks extend through openings formed in the cross head 24.

The screw 22 is held against endwise displacement from the handle and disc, but is free to turn in either direction, as the inner end of the screw is swivelled on the cross head 24, and the upper end of the screw bears against the handle. When the screw is turned the head 25 will be propelled in the handle, and the prongs or hooks will be shifted inwardly to gripping position, and outwardly from pad gripping position,

depending on the direction of turning of the screw.

In Figs. 9 to 11, inclusive, I show another form of the invention, wherein a disc 30 is used. The inner end of the screw 31 is swivelled in the disc and is provided with a washer 32 which is engaged by the shoulder 32a of the screw. On the screw 31 the cross head 33 is threaded, and to this cross head the gripping prongs or hooks 34 are positively connected, so as to move in both directions with the cross head 33.

Each hook or gripping prong is provided with a long shank 34d and with an L-shaped outer end 34b, which includes the upturned pad piercing terminal 34c. The shanks 34a slide through openings 30a formed in the disc 30. The upper end of the screw is provided with a wing head 31d, so that it may be turned by hand.

In each form of the invention scouring pad is clamped by radially disposed gripping prongs or hooks, which are shifted into clamping position by a screw mounted centrally, but the different forms show various designs for the assembly of the screw and cross heads, but in each form a cross head is employed as a connection between the screw and the gripping prongs or hooks.

By means of my invention a housewife or other person may secure a firm grip upon a standard scouring pad, and when the pad has been worn to a point of uselessness it may be readily detached and a new pad placed in position.

It is understood that various changes in the details of construction, combination and arrangements of parts, may be resorted to, within the scope of the invention, as defined by the claims hereof.

Having described my invention I claim:

1. A scouring pad holder comprising a disk having an axial bore and radial grooves in one face communicating with the bore, a cross-head

mounted for axial movement in the bore, radial arms at one end of the cross-head for cooperation with the walls of the grooves in clamping a scouring pad on the disk and means carried by the disk for advancing or retracting the cross-head and radial arms with relation to the disk.

2. A scouring pad holder comprising a disk having an axial bore and radial grooves in one face communicating with the bore, a cross-head mounted for axial movement in the bore, radial arms at one end of the cross-head for cooperation with the walls of the grooves in clamping a scouring pad on the disk, means carried by the disk for advancing or retracting the cross-head and radial arms with relation to the disk and prongs at the outer ends of the radial arms lying parallel to the axis of the disk.

3. A scouring pad holder comprising a disk having an axial bore and radial grooves in one face communicating with the bore, a cross-head mounted for axial movement in the bore, radial arms at one end of the cross-head for cooperation with the walls of the grooves in clamping a scouring pad on the disk, means carried by the disk for advancing or retracting the cross-head and radial arms with relation to the disk, the disk having an annular series of recesses opening into the bottoms of the grooves and prongs at the outer ends of the radial arms aligning with the axes of the recesses.

JOHN W. VAESSEN.
